UNITED STATES PATENT OFFICE

150,746

DESIGN FOR AN EXPANSIBLE WATCH BRACELET OR SIMILAR ARTICLE

Arthur Albanese, Providence, R. I., assignor to
Marvel Jewelry Mfg. Company, Providence,
R. I., a corporation of Rhode Island

Application July 1, 1947, Serial No. 140,036

Term of patent 7 years

(Cl. D45—4)

To all whom it may concern:

Be it known that Arthur Albanese, a citizen of the United States, residing at Providence, in the county of Providence and State of Rhode Island, has invented a new, original, and ornamental Design for an Expansible Watch Bracelet or Similar Article, of which the following is a specification, reference being had to the accompanying drawing, forming part thereof, wherein:

Fig. 1 is a top perspective view of an expansible watch bracelet or similar article embodying my new design, with portions of the chain broken away for illustrative purposes and with the links shown in full lines repeated throughout the length of the bracelet chain as indicated by the dotted lines;

Fig. 2 is a top plan view of the bracelet in an expanded position;

Fig. 3 is a bottom plan view of a section of the bracelet chain; and

Fig. 4 is a side elevational view of the section shown in Fig. 3.

I claim:

The ornamental design for an expansible watch bracelet or similar article, as shown.

ARTHUR ALBANESE.
